UNITED STATES PATENT OFFICE.

MEYER SOYBEL, OF BROOKLYN, NEW YORK, ASSIGNOR TO INTERNATIONAL FOLDING PAPER BOX CO., OF BROOKLYN, NEW YORK, A CORPORATION OF NEW YORK.

CONTAINER.

Application filed March 20, 1926. Serial No. 98,117.

My invention relates to containers and refers particularly to containers adapted to contain commodities during shipment and to expose them when offered for sale.

The particular object of my invention is a cardboard container of such shape and construction that commodities when enclosed therein will be free from danger of the container opening during shipment and handling, and which may be readily converted into an open container for the exposure of the contents for sale purposes.

It is evident that a container of this character should be firmly and safely held in closed position and that means should be supplied whereby the two opened portions may be firmly bound together to present a firm device when in this position.

The device of my invention presents a device having aforementioned valuable properties, which is economically produced, easily operated and in which the open members are firmly attached to each other.

The valuable properties of the device of my invention are evident upon a consideration of this specification and the accompanying drawings.

In the accompanying drawings illustrating one form of the device of my invention similar parts are designated by similar numerals.

Figure 1 is a perspective view of one form of my device in closed position.

Figure 2 is a plan of the blank from which the container is made.

Figure 3 is a cross-section through the line 3—3 of Figure 1.

Figure 4 is a perspective view of Figure 1 in open, or exposure, position.

Figure 5 is a cross-section through the line 5—5 of Figure 4.

Figure 6 is a cross-section through the line 6—6 of Figure 4.

The blank of the device of my invention shown in Figure 2 comprises the back member 10 having the side member 11, scored at 12, and the two end members 13 and 14 scored at 15 and 16. A slit, or opening, 17 is positioned as shown. The back 10 and the

front 18 are connected by the side 19, with scorings at 20 and 21. The side 19 has the two flaps 22 and 23 scored at 24 and 25 and is cut, or separated, at 26 and 27. The front 18 is scored at 28, and has the extended locking members 29 and 30 scored at 31 and 30.

The front 18 has the end members 32 and 33 scored at 34 and 35, a slit, or opening, 36 being positioned as shown. The member 33 has the two hook-shaped extensions 37 and 38 scored at 39 and 40. The front 18 has the side member 41 scored at 42. The side member 41 has the two flaps 43 and 44 scored at 45 and 46 and has the cut, or opening 47. The side member 19 has the angular cut 48 and the side member 41 has the angular cut 49.

Figures 1 and 3 illustrate the blank shown in Figure 2 when folded upon the scored lines, shown in dot-and-dash lines. It will be noted that that part of the device carrying the locking members 37 and 38 forms a compartment within which the front 10 extends thus binding that portion of the device together while the member 30 inserted within the slot 17 binds together the other portion of the device, the only portion requiring pasting or sealing together being portions of the side members 11 and 41. The device when in this position presents a firmly closed receptacle for commodities, such as bottles.

When the contained devices are to be exposed for sale, the device is bent upon the scored line 28, as shown in Figures 4, 5 and 6. The locking member 30 is removed from the slot 17 and inserted within the slot 36, thus firmly binding the two members 10 and 18 in open position.

It will thus be seen that the cover member 32 and the locking member 30 retain the back 10 and the front 18 together in spaced relation when the device is closed, and that the locking member 30 acts to retain the two compartments together when the device is in open position.

I do not limit myself to the particular size, shape, number or arrangement of parts as shown and described as these are given simply as a means for clearly describing the device of my invention.

What I claim is:

1. In a container capable of being formed from a blank, in combination, a front, a back, a top, a bottom and two ends, a rearwardly and downwardly extended cover carried by the front within which the upper portion of the back may be inserted when the device is in closed position, the front having a scoring across its face allowing it to be folded forwardly forming two com-

partments in the device, and locking means carried by the bottom portion of the device capable of locking it in open position.

2. In a container capable of being formed from a blank, in combination, a front, a back, a top, a bottom and two ends, a rearwardly and downwardly extended cover carried by the front within which the upper portion of the back may be inserted when the device is in closed position, the front having a scoring across its face allowing it to be folded forwardly forming two compartments in the device, a slot capable of receiving a locking flap and a locking flap carried by the bottom portion of the device capable of insertion within a slot locking the device in open position.

3. In a container capable of being formed from a blank, in combination, a front, a

rearwardly and downwardly extended cover 20 carried by the upper portion of the front and having a slot therein, a locking member carried by the bottom portion of the front, a back capable of insertion within the cover when the device is in closed position and having a slot in the lower portion thereof, a bottom, two sides, a scoring across the face of the front allowing the front to be bent forwardly and downwardly until the cover and the bottom are in a plane, the 25 locking flap being capable of placement within the slot of the cover for locking the cover and the bottom together.

Signed at New York city, in the county of New York and State of New York, this 26 19th day of March, 1926.

MEYER SOYBEL.
